(57) **CLAIM**

The ornamental design for a turn signal lamp, as shown and described.

DESCRIPTION

FIG. 1 is a rear perspective view of a first embodiment of a turn signal lamp for one side of a vehicle showing our new design.

FIG. 2 is a rear perspective view of the rear thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and,

FIG. 8 is a right side elevational view thereof.

Our novel design also includes a second embodiment for use on an opposite side of a vehicle which is mirror symmetrical to FIGS. 1-8 and therefore not separately illustrated.

Stippling and contour lines shown in FIGS. 1-8 are intended to represent approximate three-dimensional contours of the design, and are not intended to indicate surface decoration. The rear of the first embodiment and second embodiment of our new design for a turn signal lamp are devoid of surface ornamentation.

The broken lines in FIGS. 1-8 are for the purpose of illustrating environmental structure for the claimed design and form no part of the claimed design.

The stippling shown in FIGS. 1-8 is intended to represent transparent surfaces of the design, and are not intended to indicate surface decoration.

1 Claim, 4 Drawing Sheets
